UNITED STATES PATENT OFFICE.

EDWARD WILLEY MARVEL, OF PHILADELPHIA, PENNSYLVANIA.

KEY-LOCK.

1,166,380.

Specification of Letters Patent. Patented Dec. 28, 1915.

Application filed February 10, 1913. Serial No. 747,351.

To all whom it may concern:

Be it known that I, EDWARD WILLEY MARVEL, a citizen of the United States, and resident of Philadelphia, in the State of Pennsylvania, have invented a certain new and useful Improvement in Key-Locks, whereof the following is a specification, reference being had to the accompanying drawings.

10 My invention relates to locks, adapted for use in connection with safety deposit boxes and similar inclosures, normally requiring the use of two different keys to effect each opening movement of the lock; and it is the object of my invention to provide such a lock which may be set, by a key, so that it may be repeatedly operated by one key, until it is reset to be operated by two keys.

As hereinafter described, my invention includes a lock having a rotary key hub with two separate keyways, respectively for a "guard" key and a "main" key, and including mechanism whereby both of said keys are normally required to be successively inserted in said key hub to turn the latter to open the lock, but which may be so set, conveniently by said guard key, that the lock may be repeatedly operated by one other key, hereinafter termed the "master" key, until said mechanism is reset to normal condition, conveniently by the main key.

In the drawings:—Figure I is an outer face view of a lock conveniently embodying my improvement. Fig. II is a plan view of said lock. Fig. III is a vertical sectional view of the lock, taken on the line III, III in Fig. I. Fig. IV is a view similar to Fig. I but with the casing front plate removed to show the lock mechanism in normal position, requiring two keys, to wit, a guard key and a main key, to unlock it. Fig. V is a view similar to Fig. IV but showing the lock mechanism as set, by the guard key, to permit its repeated operation by the single master key. Fig. VI is a view similar to Figs. IV and V but with the lock mechanism shifted into unlocked position by the main key. Fig. VII is a view of the lock in the position shown in Fig. V but with the tumblers removed. Fig. VIII is a plan sectional view, taken on the line VIII, VIII in

Fig. VII. Fig. IX is a plan view of the key hub and cam connected therewith. Fig. X is an elevation of the guard key. Fig. XI is an elevation of the main key arranged to 55 coöperate with the guard key to unlock said lock. Fig. XII is an elevation of a master key by which the lock may be operated.

My invention includes the various novel features of construction and arrangement 60 hereinafter more definitely described.

In said drawings: 1 is the lock bolt which is fitted to slide in the lock casing 2 having the cover 3 removably secured by the screws 4 in threaded engagement with the sockets 5 in said casing. Said bolt 1 carries the stump 7 fitted to enter the gatings 8 of the tumblers 9 which are mounted to oscillate on the stud 10 which is stationary in said casing 2, but said stump 7 has the notch 12 at the 70 inner end thereof adapted to engage the serrations 13 on said tumblers when an attempt is made to retract the bolt with said gatings out of alinement with said stump. Each of said tumblers 9 is provided with a 75 spring 15, bearing at its free end upon said casing 2 and tending to thrust the tumblers downward to the position shown in Figs. IV and V. Each of said tumblers 9 is also provided with a projection 16 adapted to 80 be engaged by the hook end 17 of the detent 18 which is pivoted on the stud 19 stationary in the casing 2 and provided with the spring 23 bearing at its free end upon said casing and tending to turn said detent into engagement with said projections 16 on the tumblers 9, so as to detain the latter in locked position, as shown in Fig. IV. Said detent 85 18 has the arm 25 extending in opposition to the arm 26 of the guard lever 27, so that 90 when the latter, which is fulcrumed on the stud 29 stationary in said casing 2, is rocked from the position shown in Fig. IV to the position shown in Fig. V said detent is released from the tumblers 9 to permit the 95 latter to be turned by the key into the unlocking position shown in Fig. VI in which their gatings 8 are brought into alinement with said stump 7. Said guard lever 27 has the stump 28 adapted to enter the gatings 100 30 of the guard tumblers 31 which are pivoted on said stationary stud 19 and each pro-

vided with a spring 32 bearing at its free end upon said casing 2 and tending to turn said tumblers 31 into the position shown in Fig. IV, in which position they are stopped by their projections 34 encountering said stump 28. Said guard lever 27 has the arm 36 carrying the stud 37 which is adapted to be encountered by the releasing tumbler 38 which is pivoted on said stud 19 and provided with the spring 40 bearing at its free end upon said casing 2 and tending to turn said tumbler 38 into the position shown in Figs. IV, V and VI. It may be observed that when said guard lever 27 is turned to the position shown in Fig. V its stud 37 encounters said releasing tumbler 38 so that said guard lever may be released and restored to its normal position shown in Figs. IV and VI, by downward movement of said releasing tumbler 38. Said guard lever is also adapted to be released and returned to its normal position aforesaid by the releasing lever 42 which is fulcrumed on the screw 43 in said casing 2 and has its rear end 45 extending in co-operative relation with the arm 36 of said guard lever 27, and its opposite end 46 extending in co-operative relation with the releasing projection 47 on one of said tumblers 9.

30 The rotary key hub 50 has the cam 51 extending in the recess 52 of the bolt 1 so as to shift the latter back and forth when said hub is turned. Said hub is provided with two keyways 54 and 55 which are conveniently formed in diametrical alinement, and, when in registry with the respective slots 56 and 57 in the hub bearing 58 on said cover 3, said keyway 54 is adapted to receive the guard key 60, shown in Fig. X, and the keyway 55 is adapted to receive either the main key 61, shown in Fig. XI, or the master key 62 shown in Fig. XII. Said keys are used to manipulate said lock as follows: The lock mechanism being in the position shown in Figs. I and IV; the guard key 60 is inserted in the keyway 54 in the hub 50 and the latter turned, clockwise, approximately sixty degrees, the shape of said recess 52 being such as to permit such movement of the cam 51 without shifting the bolt 1. Said key 60 is bitted so as to sweep the tumblers 31 into position to receive the stump 28 in their gatings 30 and to then turn said lever 27 into the position shown in Fig. V, the projection 64 on said cam 51 being so shaped as to encounter the shoulder 65 on said lever to turn the latter. Thereupon, said hub 50 being returned to its normal position shown in Figs. I and IV, and said key 60 being withdrawn, the lock is in condition to be operated to retract the bolt 1 by the main key 61 shown in Fig. XI. Said main key 61 being then inserted in the keyway 55 of the hub 50 the latter is turned, clockwise, from the position shown in Fig.

V to the position in Fig. VI. Said key 61 is bitted so as to sweep the tumblers 9 into position to receive the stump 7 in their gatings 8 thus permitting the cam to turn to the position shown in Fig. VI in which the slide bolt 1 is fully retracted. It may be observed, with reference to Fig. VI, that the unlocking movement last described, causes the releasing projection 47 to encounter the end 46 of the releasing lever 42 and turn the latter from the position shown in Fig. V to the position shown in Fig. VI so as to release the guard lever 27, from the detent 18 so that the latter is ready to reengage the projections 16 on said tumblers 9 when the latter are freed from the stump 7 by the locking movement of the slide bolt 1. Moreover, such releasing movement of the guard lever 27, from the position shown in Fig. V to the position shown in Fig. VI, frees the guard tumblers 31 from the stump 28 and permits them to return to their normal position with their projections 34 against said stump. Therefore, when the lock is thus operated by the guard key 60 and the main key 61, both of said keys are required to effect each opening movement of the lock. However, when the lock mechanism is set into the position shown in Fig. V, by the operation of the guard key 60 as above described, the lock may be repeatedly operated by a single key, to wit, the master key 62, shown in Fig. XII. It may be observed that although said master key 62 is inserted in the same keyway 55 as the main key 61, to wit, the keyway 55 of the hub 50, and turned in the same direction, said key 62 is so bitted that it does not raise the tumbler 9 having the releasing projection 47, and consequently operation of the lock by said key 62 does not operate the releasing lever 42. Therefore, the detent 18, guard lever 27, guard tumblers 31 and the parts associated therewith remain in the inoperative position shown in Fig. V, during the repeated operation of the lock by the key 62. In order to permit such operation, the tumbler 9 provided with the releasing projection 47 has the auxiliary gating 65 to receive said stump 7. It is to be understood that both of said groups of tumblers 9 and 31 are changeable to form different combinations requiring keys with correspondingly changed bittings to operate them. Moreover, it is to be understood that I do not desire to limit myself to the precise details of construction and arrangement herein set forth as it is obvious that various modifications may be made therein without departing from the essential features of my invention as defined in the appended claims.

I claim:

1. In a key lock, the combination with a slide bolt; of mechanism arranged to normally detain said bolt in locked position, so

constructed and arranged as to require the operation of two keys to unlock said bolt; and change mechanism whereby the other mechanisms aforesaid may be set to permit 5 the lock to be operated by one key.

2. In a lock, the combination with a slide bolt; of tumbler mechanism arranged in two groups normally requiring two keys to unlock said bolt, and mechanism whereby the 10 lock may be set to be operated by one key.

3. In a changeable combination key lock, the combination with a slide bolt; of a rotary key hub with two separate keyways, respectively for a guard key and a main 15 key; main tumbler mechanism arranged to detain and release said bolt in accordance with the position thereof, guard tumbler mechanism arranged to detain and release said bolt in accordance with the position 20 thereof, including a guard lever in co-operative relation with a pivoted detent for said main tumblers; releasing mechanism, including a releasing tumbler in the group of main tumblers, and a releasing lever 25 operatively connecting said releasing tumbler with said guard lever, arranged to release said detent; whereby a guard key and a main key are normally required to be successively inserted in the respective key- 30 ways in said key hub to turn the latter to open the lock, but said guard key may be turned to set the lock mechanism so that it may be repeatedly operated by another key, inserted in the main keyway, until the 35 lock is reset to normal condition by said main key.

4. In a changeable combination key lock, the combination with a slide bolt; of a rotary key hub with two separate keyways, 40 respectively for a guard key and a main key; main tumbler mechanism arranged to detain and release said bolt in accordance with the position thereof; guard tumbler mechanism arranged to detain and release said bolt in accordance with the position 45 thereof, including a guard lever in co-operative relation with a detent for said main tumblers; releasing mechanism, including a releasing tumbler, and a releasing lever 50 operatively connecting said releasing tumbler with said guard lever, arranged to release said detent; whereby a guard key and a main key are normally required to be successively inserted in the respective keyways 55 in said key hub to turn the latter to open the lock, but said guard key may be turned to set the lock mechanism so that it may be repeatedly operated by another key.

5. In a changeable combination key lock, 60 the combination with a slide bolt; of a rotary key hub with two separate keyways, respectively for a guard key and a main key; main tumbler mechanism arranged to detain and release said bolt in accordance with the position thereof; guard tumbler 65 mechanism

arranged to detain and release said bolt in accordance with the position thereof, including a pivoted detent for said main tumblers; releasing mechanism, including a releasing tumbler in the group of main 70 tumblers, and a releasing lever operatively connecting said releasing tumbler to release said detent; whereby a guard key and a main key are normally required to be successively inserted in the respective keyways 75 in said key hub to turn the latter to open the lock, but said guard key may be turned to set the lock mechanism so that it may be repeatedly operated by a single key.

6. In a changeable combination key lock, 80 the combination with a slide bolt; of a rotary key hub with two separate keyways, respectively for a guard key and a main key; main tumbler mechanism arranged to detain and release said bolt in accordance 85 with the position thereof; guard tumbler mechanism arranged to detain and release said bolt in accordance with the position thereof, including a detent for said main tumblers; releasing mechanism, including a 90 releasing tumbler in the group of main tumblers, and means operatively connecting said releasing tumbler to release said detent; whereby a guard key and a main key are normally required to be successively inserted in the respective keyways 95 in said key hub to turn the latter to open the lock, but said guard key may be turned to set the lock mechanism so that it may be repeatedly operated by a single key.

7. In a changeable combination key lock, 100 the combination with a slide bolt; of a rotary key hub; main tumbler mechanism arranged to detain and release said bolt in accordance with the position thereof; guard tumbler mechanism arranged to detain and release said bolt in accordance with the position thereof, including a detent for said main tumblers; releasing mechanism, including a 105 releasing tumbler in the group of main tumblers, and means operatively connecting said releasing tumbler to release said detent; whereby a guard key and a main key are normally required to be successively inserted in said key hub to turn the latter to open 110 the lock, but said lock mechanism may be set so that it may be repeatedly operated by a single key.

8. In a changeable combination key lock, 115 the combination with a slide bolt; of a rotary key hub; main tumbler mechanism arranged to detain and release said bolt in accordance with the position thereof; guard tumbler mechanism arranged to detain and release said bolt in accordance with the 120 position thereof, including a detent for said main tumblers; releasing mechanism, including a releasing tumbler and a releasing lever operatively connecting said 125 releasing tumbler to release said detent; 130

whereby a guard key and a main key are normally required to be successively inserted in said key hub to turn the latter to open the lock, but said lock mechanism may be set so that it may be repeatedly operated by a single key.

In testimony whereof, I have hereunto

signed my name at Philadelphia, Pennsylvania, this sixth day of February, 1913.

EDWARD WILLEY MARVEL.
